UNITED STATES PATENT OFFICE.

ISAAC E. SHUMAKER, OF DEANVILLE, PENNSYLVANIA.

REAPING-MACHINE ATTACHMENT.

SPECIFICATION forming part of Letters Patent No. 716,120, dated December 16, 1902.

Application filed November 28, 1898. Serial No. 697,675. (No model.)

To all whom it may concern:

Be it known that I, ISAAC E. SHUMAKER, a citizen of the United States of America, residing at Deanville, in the county of Armstrong and State of Pennsylvania, have invented certain new and useful Improvements in Reaping-Machine Attachments, of which the following is a specification.

This invention relates to reaping-machines, and is particularly adapted to be used in combination with that part known as the "table" or "platform."

The object of the invention is to hold the grain or grass on the platform when reaping on hillsides or uneven ground and to dump the same when a desired amount is collected thereon.

Another object of this invention is to provide such a device which is automatic, easily and quickly applied, exceedingly cheap and simple in its construction, and one that will efficiently perform all of its intended functions.

With these objects in view and such others as may appear my invention consists in the particular construction of the various parts and in the novel manner of combination or arrangement of said parts, all of which will be described hereinafter and pointed out in the claims.

In the drawings forming a part of this specification, Figure 1 is a perspective view of a reaping-machine platform, showing my invention as applied; Fig. 2, a detail view of the drop-board with arm attached.

Referring by letters to the drawings, A represents the platform of a reaping-machine, having attached to its outer edge by hinges B a drop-board C, which is substantially oval in shape and provided upon one end with an arm D, so constructed that it will not catch and drag the grain or grass. To the free end of this arm is attached a spiral spring E, which is connected to a stay F, secured to the rear end of the platform and provided with a series of apertures G, adapted to receive the spring, thus affording means for adjusting the tension, so as to regulate the device for cutting either light or heavy grain. The drop-board is tripped by the weight of the grain. Thus the tension should be adjusted accord-

ing to the thickness or thinness of the grain in which the machine is working, so as to deposit the bundles in piles of equal sizes.

It will be understood that when the weight of the grain upon the inclined platform reaches a predetermined amount the drop-board will be swung outward and downward thereby automatically, thereby releasing the material.

The side H is detachably secured to the outer edge of the platform A by means of strips I, which fit within apertures formed within cleats J, extending from under the platform. The stay F is preferably secured to this detachable side.

It will thus be seen that I provide a device that will efficiently perform all of its intended functions and one that will be readily understood by all conversant in such matters, the extreme simplicity rendering an elaborate description unnecessary.

Having thus described my invention, what I claim as new, and desire to secure by Letters Patent, is—

1. In a reaping-machine attachment, the combination with a platform having sides thereto; of a drop-board hinged to one end of the platform and between the sides thereof, an arm extending from the outer edge of the drop-board to a point adjacent to one side, a stay secured to said side and having a series of apertures therein, and a spiral spring secured at opposite ends to said arm and in one of the apertures of the stay, respectively. 85

2. In a reaping-machine attachment, the combination, with a platform having cleats thereunder; of a detachable side upon the cleats, strips secured to said side and adapted to engage the cleats and retain the side in position, a stay secured to the side and having a series of apertures therein, a drop-board hinged to, and arranged along one edge of the platform and adjacent to the side, an arm extending from the outer edge of the drop-board, and a spiral spring secured at opposite ends to said arm and in one of the apertures in the stay, respectively. 95

ISAAC E. SHUMAKER.
